UNITED STATES PATENT OFFICE

ARTHUR VON FRANKENBERG, OF NEW YORK, N. Y.

DESIGN FOR A LAMP

Application filed August 29, 1931. Serial No. 40,953. Term of patent 3½ years.

To all whom it may concern:

Be it known that I, ARTHUR VON FRANKENBERG, a citizen of the United States of America and a resident of New York city, in the county and State of New York, have invented a new, original, and ornamental Design for a Lamp, of which the following is a specification, reference being had to the accompanying drawings, forming part hereof.

Figure 1 of the accompanying drawings is a perspective view of my new design for a lamp, showing the lamp in vertical position.

Figure 2 is a perspective view of the upper portion of the lamp shown in Figure 1, showing the appearance thereof when the lamp has been rotated through an angle of about 110°.

The lamp may be rotated about a horizontal axis as indicated for illustration in Fig. 2.

I claim:

The ornamental design for a lamp, as described and shown.

ARTHUR VON FRANKENBERG.
